CONSTRUCTION HORSE

James L. Hollingsworth, 207 Cole Road,
Greenville, S.C. 29203

Filed Aug. 24, 1967, Ser. No. 8,378

Term of patent 14 years

U.S. Cl. D54—1
Int. Cl. D8—03

Fig. 1.

Fig. 2.

FIGURE 1 is a perspective view of a construction horse embodying my new design, and

FIGURE 2 is an enlarged perspective view of an end member of the construction horse illustrated in FIGURE 1.

The dominant features of my design reside in the portion shown in full lines.

I claim:

The ornamental design for a construction horse, substantially as shown and described.
